GOLD RECOVERY DEVICE

Mose D. East, Seattle, Wash.

Application January 16, 1934, Serial No. 706,889

5 Claims. (Cl. 209—208)

My present invention relates to the art of suction dredges and more particularly to a dredge which because of its peculiar construction is particularly adapted as a gold recovery dredge.

Dredging for gold is one of the earliest forms of gold mining and is quite well developed. However, there are many instances where existing equipment cannot be successfully used. This is particularly true in deep or fast running water or where the bottom of a stream is so rough and rocky that ordinary types of dredges cannot remove the gold bearing sand and gravel from the seams, cracks and depressions under the water. My present machine has been provided to supply a solution for problems of this character.

The principal object of my invention is to provide a light portable machine which lends itself to the difficult recovery of gold that cannot be expected from the larger pieces of equipment of the conventional construction.

It is further the purpose of my present invention to create a suction dredge in which vacuum is applied to the suction line so as to so increase the velocity of the suction stream that particles of gold will be lifted that normally would float downwardly thru the ascending stream of water and to further provide that the pump need not handle the sand and gravel picked up.

A further object of my present invention is to provide in combination with such a machine a suction nozzle arrangement so constructed that recoveries can be made from small depressions, crevices and the like and at the same time the device cannot be plugged by a single rock.

Other and more specific objects will be apparent from the following description taken in connection with the accompanying drawings, wherein

Figure 1 is a top plan view of a dredge built after the teachings of my invention. Figure 2 is a side elevation in section taken along the line 2—2 of Figure 1. Figure 3 is a top plan view of a portion of Figure 1 but showing a different connection of the water pump and collecting chambers as it is used in making the clean up of the dredge. Figure 4 is a vertical sectional view thru the vacuum tank and collecting chamber illustrating the normal flow when the machine is making a suction lift. Figure 5 is a fragmentary sectional view thru the end of my suction nozzle.

Referring to the drawings, throughout which like reference characters indicate like parts, numerals 8 and 9 designate the settling chambers of my device of which there should not be less than two. The exact shape of these chambers

is a matter of individual design but by virtue of the fact that considerable negative pressure is created within the tanks it is found most desirable to use boiler like construction having the belled-out top and bottom illustrated and preferably having reasonable height with respect to their diameter as this relationship facilitates the separation. In the present design I have illustrated the two settling chambers 8 and 9 as being both connected to a single vacuum tank 10, the connections being each provided with shut-off valves 12 so that tank 10 may be connected, at will, with either of the two tanks or with both at the same time if desired. An intake from the suction nozzle is provided near the top of each of the settling chambers and as a matter of convenience I provide that the two inlets as 14 and 15 be led to a Siamese fitting 16 which is connected to the suction line 18 which leads in turn to the suction nozzle 20. I further provide each of the inlet openings 14 and 15 with shut-off valves as 22 and 24 respectively.

About half way up on tanks 8 and 9 I provide suction outlets as 26 and 28. These two outlets are led to a common Siamese fitting 30 which in turn is connected to the suction side of a water pump 32. Shut-off valves for the suction outlets 26 and 28 are indicated at 34 and 36. I have further provided at 38 a T fitting in the pump suction line 40 and have provided a shut-off valve 42 so that a different arrangement of piping may be provided as is illustrated in Figure 3. A discharge line, preferably a hose, is provided for the water pump as 44. Water pump 33 may be driven from any suitable source of power such as the gasoline engine 46 illustrates. Inasmuch however as it may not be desirable to operate the water pump at all times it is provided with a friction clutch 48 so that the water pump may be disengaged from the power supply.

Further, a vacuum pump 50 is connected to the motor 46. A suction line 52 leads from vacuum pump 50 to tank 10.

As a means for maneuvering my device I have provided the transversely disposed shaft 54 having a plurality of cable drums thereon as 55 and 56. Shaft 54 is optionally connected thru suitable gearing and the clutch 58 to the motor 46.

Method of operation

In operating my device the prime mover as the motor 46 is started. This drives the vacuum pump 50 which thru its connecting piping exhausts the air from tank 10 and from either of the settling chambers 8 or 9 depending on which

one it is connected to. When a reasonable amount of vacuum is produced in the system the water pump 32 is then engaged and a flow of material started after the showing of Figure 4.

- 5 It of course will be understood that in order to build up vacuum within the system it will be necessary that either the nozzle 20 be submerged or the suction shut-off valve be closed.
- The construction of the suction nozzle will 10 probably best be understood from Figure 5 in which a piece of pipe 60 is employed which should be longer than the depth of water the device will be used in. The most satisfactory means of directing the nozzle is by an operator on the 15 surface of the water. A suction hose as 18 is provided to connect pipe 60 to the settling chambers. Now, it has often been found that rock would obstruct the relatively small nozzle opening and to prevent this I have provided a plurality of downwardly and inwardly extending fingers as 62. These I prefer to grip as by the set collar 64 and to have them guided by the flange 66. Compression springs are employed around each of the fingers 62 and disposed between flange 25 66 and collar 64. These are illustrated at 68. Now, normally in use the operator presses down on pipe 60 to such an extent that the fingers 62 are imbedded in notches 10, cut in the end of pipe 60. Then as he twists the pipe around to 30 loosen up the gravel, fingers 62 tend to agitate the surface immediately adjacent the suction stream so that the finer gold and sand are disturbed and made more easily liftable. If, however, a rock becomes lodged over the end of the 35 tube 60 the operator need merely to lift up on the tube and the compression springs 68 will push the fingers outwardly to about the position shown in Figure 5. This will hold the obstructing rock away from the end of the nozzle and the large 40 area between the end of the nozzle and the stone would be such that the suction would be broken on the blocking stone and the same released.

Referring now to Figure 4 the stream of material incoming thru hose 18 is deposited in the 45 settling chamber. The larger stones, the heavier gravel and sand together with the larger particles of gold will settle into the bottom of the settling chamber. The lighter materials will be drawn off thru the suction outlet pipes as 26 or 50 28. This material will be passed out thru the discharge 44 and will be further separated in riffles, sluices or other desirable separation means. One of the important features of my present equipment is the velocity obtained in 55 intake 18. This is greater than can be accomplished normally by a suction water pump by virtue of the fact that the vacuum pump 50 is adding to that lift. Further, in order that the water pump will not work against itself I have 60 provided a connection 12 which connects the vacuum tank 10 to the suction side of the water pump. The height of water in the settling chamber can be determined at all times by the water gauge glasses 74 and 75. This also gives 65 an index as to when the sand has risen too high within a settling chamber. At this time the settling chamber being used is shut-off and its companion chamber used. The settling chamber which has been used must then be cleaned. This 70 is accomplished by means of the discharge outlet 76 which is closed by valve 78 and the hand hole plate 80. If additional water is required in the system it can be supplied by using a suction line as 82 attached to valve 42 in the water pump line 40 and connecting the normal discharge pipe

44 to the Siamese fitting 16 in place of the normal suction hose 18. When this is being so used, however, it will be necessary that valves 34 and 36 be closed.

One feature of this construction, which it is believed will be apparent, is that of not passing thru water pump 32 any of the large scouring materials, it being so arranged so that the heavier materials are deposited in the lower half of the settling tank and when they have accumulated to a point where they would normally be drawn thru the water pump the alternate tank is to be used. The use of the alternate tank saves a great deal of time as in so many instances the heavier material will be held in suspension for 15 some time and by having two tanks for alternate use the settling can be carried on so that the cleaning out of the settling chambers can be deferred for quite a period of operation.

Vacuum tank 10 has been provided, together 20 with gauge glass 74, so that the operator of the dredge will have ample warning of the raising of the water level in the settling tank and further, should there be a failure of the water pump the capacity of tank 10 should be sufficient so that 25 the operator will have ample time to shut valve 12 and thus prevent any water or sand being taken into the vacuum pump 50. In this connection it should be understood that the type of pump most suitable for creating the vacuum, 30 in a dredge of this type, is one of light weight. This in turn necessitates high speed and delicate internal construction for the pump so that any solid material, even water, entering the pump might cause its destruction. Tank 10 should 35 therefore be preferably mounted well above the normal water level of the settling tanks and the outlet pipe 52 should be taken off the upper-most part of tank 10 to further insure pump 50 against damage.

The foregoing description and the accompanying drawings are believed to clearly disclose a preferred embodiment of my invention but it will be understood that this disclosure is merely 45 illustrative and that such changes in the invention may be made as are fairly within the scope and spirit of the following claims.

Having thus fully described my invention, what I claim as new and desire to secure by Letters Patent is:—

1. In a dredging apparatus, the combination with a closed tank forming a settling chamber, of a vacuum tank located above the tank and communicating directly therewith above the settling chamber, means for controlling communication between said tanks, a vacuum pump connected with the vacuum tank, an intake pipe connected with the upper portion of the settling tank, a submerged nozzle at the free end of the intake pipe, a normally closed draw-off pipe 60 at the bottom of the settling chamber, and a suction-outlet pipe connected to the settling chamber between the intake pipe and the draw-off pipe.

2. In a dredging apparatus, the combination 65 with a pair of closed, separate, tanks forming settling chambers and a vacuum tank located above and directly communicating with both settling chambers, of an intake pipe having a Y-connection with said settling chambers and means 70 for controlling flow of material through said Y-connection to the chambers, a submerged nozzle at the free end of the intake pipe, a draw-off pipe at the bottom of each settling chamber and a control valve in each pipe, a suction-pump 75

and a suction outlet-pipe connected to said settling chambers intermediate the intake and draw-off pipes, and a vacuum pump connected with said vacuum tank.

5. 3. In a dredging apparatus, the combination with a tank forming a settling chamber, a vacuum tank located above and communicating with the first tank above its settling chamber means for controlling communication between said tanks, and a vacuum pump connected with the vacuum tank, of an intake pipe having a submerged nozzle and connected with the upper part of the settling tank, a draw-off pipe connected to the lower part of the settling tank, 10 a water gauge connected with the settling tank below the intake pipe, a water-pump, and a suction outlet-pipe connecting said pump with the settling tank intermediate the intake pipe and the draw-off pipe.
- 15 4. In a dredging apparatus, the combination with a settling tank and a vacuum tank, a pipe connecting said tanks and a control valve in said pipe, of a motor, a water pump and driving means between said motor and pump, a suc-

tion outlet-pipe connecting said pump and the settling tank, a vacuum pump and driving means between said motor and the vacuum pump, a vacuum pipe connecting the vacuum pump and the vacuum tank, and a clutch device included in the driving means between the motor and the water pump.

5. 5. In a dredging apparatus, the combination with a pair of settling tanks forming separate chambers and a vacuum tank located above and connected with said tanks above said chambers, of an intake-pipe having a connection with each settling tank, a draw-off pipe at the bottom of each settling tank and a valve for each pipe, a valve for controlling communication of the intake pipe with each settling chamber, a water pump and a water pipe from said pump communicating with each settling chamber intermediate the intake pipes and the draw-off pipes, 10 a valve for controlling exit of water through each water pipe, and a water connection between said pump and the intake pipe.
- 15 20
